UNITED STATES PATENT OFFICE.

JOHN G. HAGLOCK, OF STERLING, ILLINOIS.

DESIGN FOR A HAME-TUG MEMBER.

SPECIFICATION forming part of Design No. 31,469, dated August 29, 1899.

Application filed May 29, 1899. Serial No. 718,753. Term of patent 14 years.

To all whom it may concern:

Be it known that I, JOHN G. HAGLOCK, a citizen of the United States, residing at Sterling, in the county of Whiteside and State of Illinois, have invented and produced a new and original Design for a Hame-Tug Member, of which the following is a specification, reference being had to the accompanying drawings, forming part thereof.

Figure 1 is a perspective of my hame-tug member. Fig. 2 is a side elevation of the same.

Similar letters refer to similar parts in both views.

As shown in the drawings, the hame-tug member comprises two parallel side bars D, having their forward portions curved upwardly and provided at their upper forward ends with short extremities or projections D'

opposite to and extending toward each other. At their rear ends the side bars D are con-

nected by a cross-bar E, and between this cross-bar E and the forward ends a cross-bar F extends between the side bars. Projecting forwardly from the cross-bar F and between the side bars is a tongue B, which is provided with apertures B'.

The leading or essential feature of the design is the member having side bars curved upward at their forward ends and provided with the opposite inwardly-projecting extremities, the cross-bar having the forwardly-projecting tongue and the rear cross-bar.

Having thus described my invention, what I claim, and desire to secure by Letters Patent, is—

The design for a hame-tug member, substantially as shown and described.

JOHN G. HAGLOCK.
